Patented Oct. 5, 1976

241,742

OPTICAL GUN SIGHT

William F. Steck III, El Paso, Tex., assignor to
W. R. Weaver Company, El Paso, Tex.

Filed Sept. 22, 1975, Ser. No. 615,263

Term of patent 14 years

Int. Cl. D16—06

U.S. CL. D16—60

FIG-1

FIG-4

FIG-2

FIG-3

FIG-5

FIG. 1 is a side elevational view of an optical gun sight, both sides being identical;

FIG. 2 is a top plan view;

FIG. 3 is a bottom plan view;

FIG. 4 is an end elevational view taken at the ocular end of the optical gun sight; and

FIG. 5 is an end elevational view taken at the objective end of the optical gun sight.

I claim:

The ornamental design for an optical gun sight, as shown and described.
